ATTORNEYS.

UNITED STATES PATENT OFFICE.

JOHN A. OST, OF LOS ANGELES, CALIFORNIA.

DEVICE FOR FORMING BRAIDLIKE DECORATIONS.

Application filed November 15, 1927. Serial No. 233,454.

My invention relates to devices adapted to be used for decorative purposes, and it has special reference to a device by means of which even an unskilled person may be able to produce decorations of a pleasing appearance out of a plastic substance wherever desired upon a suitable surface.

The main object of the invention is to provide a device of this character with receiving means for a plastic substance, such as sugar paste, plaster, papier mâché, or the like, and to provide means whereby a twirling motion may be imparted to the substance, as it is forced out of the receiving means, so that the substance, when ejected, may be of a braid-like form, and that the device may be adapted for producing such decorations as often are required in various arts. Thus, although the device preferably is applied in the baker's and confectioner's art for producing braid-resembling decorations of sugar paste on cakes, or the like, it also, according to the nature of the plastic substance in the receiving means of the device, may be applied for decorative purposes on furniture, on walls and ceilings and on other things or articles, too numerous to be mentioned in detail, such applications of the device easily suggesting themselves from the construction and the operation of the device.

Another object of the invention is to provide a device of this character with interchangeable nozzles through which the plastic substance is ejected from the receptacle therefor, so that even an unskilled person may be able to produce a number of different designs of braid-like decorations in the substance when it is ejected from the device.

A further object of the invention is to provide a device of this character with a rotatable outlet member in the receptacle for the plastic substance, and to provide the rotatable member with means, which, without interfering with the ejection of the substance from the receptacle, is adapted to be engaged by a manually operable element in order to cause rotation of the member, and to construct the device so that the operating element is readily insertable into or withdrawable from the receptacle.

With the above mentioned objects and with other objects in view, the invention consists in the novel construction and combination of parts hereinafter described, illustrated in the accompanying drawings, and set forth in the appended claims, it being understood that various changes in the form, proportion, size and minor details of construction within the scope of the claims may be resorted to without departing from the spirit, or without sacrificing any of the advantages, of the invention.

In the drawings,

Figure 1 is a longitudinal, mid-sectional view of the device and shows the operating element as being inserted into the receptacle for the plastic substance and as engaging the rotatable member in the receptacle;

Figure 2 is an enlarged view, showing in elevation the inner end portion of the operating element in engagement with the transverse pin in the rotatable member, the pin being shown in section;

Figure 3 is an enlarged end view of the form of nozzle attached to the receptacle shown in Figure 1, the nozzle in this instance being provided with two cylindrically shaped openings for the ejection therethrough of the plastic substance;

Figure 4 is an enlarged elevation of a portion of the plastic substance ejected from a rotating nozzle of the type shown in Figures 1 and 3;

Figure 5 is a perspective view of a nozzle having three cylindrical openings for the ejection therethrough of the plastic substance;

Figure 6 is an enlarged elevation of a portion of the plastic substance ejected from a rotating nozzle of the type shown in Figure 5;

Figure 7 is an end view of the nozzle having four cylindrical openings for the ejection therethrough of the plastic substance;

Figure 8 is an enlarged elevation of a portion of the plastic substance ejected from a rotating nozzle of the type shown in Figure 7;

Figure 9 is an end view of a nozzle having a cross-sectionally square opening for the ejection therethrough of the plastic substance;

Figure 10 is an enlarged elevation of a portion of the plastic substance ejected from a rotating nozzle of the type shown in Figure 9;

5 Figure 11 is an end view of a nozzle having a cross-sectionally rectangular opening for the ejection therethrough of the plastic substance;

10 Figure 12 is an enlarged elevation of a portion of the plastic substance ejected from a rotating nozzle of the type shown in Figure 11; and

15 Figure 13 is an end view of a nozzle having two cross-sectionally star-shaped openings for the ejection therethrough of the plastic substance.

20 My invention comprises a device which, in a general way, is indicated in Figure 1 by the numeral 1. This device is provided with a receptacle 2 which may be constructed of any suitable material and in any approved manner so as to be compressible or otherwise to have compression means in connection therewith. Preferably, however, 25 the receptacle is made of a suitable flexible material, such as rubber, specially treated cloth, or the like, so that the receptacle is adapted to hold therein a plastic substance, such as sugar paste, plaster, papier mâché, 30 or, in fact, any plastic substance adapted to be twisted or otherwise shaped, while in its plastic state, so that braid-like decorations may be formed thereof. Although the receptacle 2 may be formed in any suitable 35 manner, I prefer to make it somewhat pear-shaped; that is, to make it narrow at one end, as shown at 3, and widened adjacent to its other end 4, as shown at 5, so that the receptacle may be conveniently grasped and 40 compressed by a person's hand and that thus, when the receptacle has a plastic substance therein, the substance may be easily ejected from the receptacle. At its narrow 45 end 3 the receptacle is open and adapted to be slipped over the inner end of a ferrule 6 so as to form a tight joint with the ferrule, and at its opposite end 4 the receptacle is 50 preferably of a tube-like form and considerably smaller in diameter than at the end 3, so as to be adapted to receive and to hold 55 therein one end of a bearing member in the form of a sleeve 7 and to be tightly joined to the sleeve, which preferably is of such a length that the sleeve is normally adapted to extend partly into the ferrule.

60 A shaft or element 8 is rotatably mounted in the sleeve and terminates outside thereof at the end 4 of the receptacle in a crank portion 9, and with its other end the shaft 65 extends beyond the sleeve and is in the end provided with a slot 10. Preferably, the shaft has secured thereon by any suitable means collars 11 in order to prevent an excessive endwise movement of the shaft in the sleeve.

In its outer end the ferrule 6 has a central opening 12, so that an annular flange 13 is thereby formed at the end of the ferrule. A bushing 14, provided with a central, longitudinal opening 15 therein and comprising an externally threaded stem 16, at one end of which is formed an annular flange 17, is adapted to be rotatably mounted with the stem in the opening 12 and with the flange 17 to contact the inner side of the flange 13, and a nut 18 is screwed upon the stem outside of the flange 13 sufficiently close thereto for preventing an excessive endwise movement of the bushing while at the same time allowing the bushing to rotate freely in the ferrule 6. In the bushing is a pin 19, which extends transversely through the bushing and the opening 15 therein and is adapted to fit in the slot 10 at the end of the shaft 8, so that, by the rotation of the shaft, a rotative movement may simultaneously be imparted to the bushing.

25 A tapered nozzle, which in Figures 1 and 3 is indicated by the numeral 20, is at its wide end internally threaded and is thereby 30 adapted to be screwed tightly against the nut 18 upon the stem 16 for locking the nut in its adjusted position so that the nozzle 20 and the bushing 14 may be considered as one member which is rotatably attached to the receptacle 2. The nozzle is in these 35 figures shown as provided with outlet means in the form of two cylindrical openings 21 adjacent to each other. Preferably, the nut has a knurled outer surface, and the nozzle 40 has a similarly knurled outer surface at its wide end, as indicated in Figure 5 at 22 on a nozzle 23, in order to facilitate the adjustment of the nut and the nozzle upon the 45 stem 16 and to dispense with the use of wrenches or other tools for accomplishing the adjustment.

50 The nozzle 23 is shown as provided with three cylindrical outlet openings 24 adjacent to one another, while in Figure 7 is 55 shown a nozzle 25, provided with four cylindrical outlet openings 26, and in Figure 13 is shown a nozzle 27, in which two cross-sectionally star-shaped outlet openings 28 are formed adjacent to each other. If so 60 desired, a nozzle may be provided with only one outlet opening of a special shape. For instance, in Figure 9 is shown a nozzle 29 provided with an outlet opening 30, which is square in cross-section, and in Figure 11 is shown another nozzle 31, provided with an 65 outlet opening 32, which is rectangular in cross-section. All the nozzles 20, 23, 25, 27, 29 and 31, of course, are merely illustrative and readily suggest a multitude of other nozzles, with outlet openings of different 70 shapes and arrangements.

75 When the receptacle has therein a plastic substance, which may be sugar paste, such as used by bakers or confectioners, or any 80

other substance in a plastic state so that the substance easily may be given various shapes, and when the shaft 8 engages the pin 19, as shown in Figures 1 and 2, the operator takes 5 hold of the receptacle 2 and compresses it with one hand, while with the other hand he turns the crank 9. While in this manner the plastic substance is forced through the opening 15 in the bushing 14 and thence is 10 forced into the nozzle so as to be ejected through the outlet opening or openings therein, it is at the same time twisted, so that a braid-like shape of a pleasing appearance is given thereto. It being assumed that 15 the nozzle 20 is screwed upon the bushing 14, as before described, the plastic substance ejected from the outlet openings 21 of the nozzle will have the appearance of a two-ply cord, as shown at 33 in Figure 4. When the 20 nozzle 23 is used in connection with the receptacle 2, the plastic substance ejected from the nozzle will have the appearance of a three-ply cord 34, as shown in Figure 6, and when the nozzle 25 is used the ejected plastic 25 substance will appear like a four-ply cord 35, as shown in Figure 8. The plastic substance ejected from the nozzle 29, on account of the rotary motion of the nozzle, will have the appearance of a twisted square rod 36, as 30 shown in Figure 10, and the plastic substance ejected from the rotating nozzle 31 will appear like a twisted flat band 37, as shown in Figure 12.

When the nozzle 27 is attached to the 35 receptacle 2 and is caused to rotate, and when the plastic substance in the receptacle is caused to issue from the outlet openings 28 in the nozzle, it will appear somewhat like the formation 33, with the difference 40 that the imitations of plies are star-shaped instead of circular in cross-section, as shown in Figure 4. However, since imitations of cross-sectionally star-shaped plies easily may be understood from the appearance of the 45 formation 33, an exact illustration thereof is deemed superfluous and is, therefore, omitted.

In order to place the plastic substance in the receptacle 2, the nozzle is removed from 50 the bushing 14, and the substance is injected into the receptacle through the opening 15 in the bushing. If so desired, however, the receptacle may be removed from the ferrule 6, and the substance may then be injected 55 through the opening at the end 3 into the receptacle, which is thereafter again slipped into engagement with the ferrule, as shown in Figure 1. The sleeve 7, with the shaft 8 therein, may be pulled out of the receptacle 60 through the end 4 in order to make the shaft and the sleeve, as well as the interior of the receptacle, readily accessible for cleaning purposes.

From the foregoing, it is clear that, by

using in connection with the device 1 nozzles which have therein outlet openings of different shapes and arrangements, it is possible to form a plastic substance into a great variety of different designs of braid-like decorations, which are applicable in many arts for the purpose of producing pleasing effects. For example, with reference to sugar paste, it is understood that many highly artistic ornaments, not possible to produce without causing a twisting motion 75 of the substance, may easily be applied to cakes, confectionery or the like, even by an unskilled person that is using the device 1.

I claim as my invention:

1. A device of the character described, 80 comprising a receptacle adapted to receive a plastic substance therein and provided at one end with an outlet opening and at its other end with another opening, the receptacle being made of a flexible material so that the receptacle is adapted to be compressed and that thereby the substance may be forced through the outlet opening; a member adapted to be rotatably attached to the receptacle at the outlet opening and provided 85 with an opening connected with outlet means through which the substance forced from the receptacle may be ejected from the member; a bearing member adapted to be removably fitted in the other opening in the receptacle 90 so as to form a tight joint with the receptacle and to extend therein; and an element rotatably mounted in the bearing member and extending beyond the bearing member so as to be adapted to engage the 95 rotatable member, the element and the rotatable member being provided with means for engaging each other so that, when the element is rotated, a simultaneous rotative movement is imparted to the rotatable member, and that thus the substance ejected 100 through the outlet means in the rotatable member may be of a braid-like form, as, and for the purpose, set forth.

2. A device of the character described, 110 comprising a receptacle adapted to receive a plastic substance therein and provided at one end with an outlet opening and at its other end with another opening, the receptacle being made of a flexible material so that the receptacle is adapted to be compressed and that thereby the substance may be forced through the outlet opening; a member adapted to be rotatably attached to the receptacle at the outlet opening and provided 115 with an opening connected with outlet means through which the substance forced from the receptacle may be ejected from the member; a pin secured in the member and extending across the opening therein; a sleeve adapted to be removably fitted in the other opening in the receptacle so as to 120 form a tight joint with the receptacle and

to extend therein; and a shaft rotatably mounted in the sleeve and provided at its end outside of the receptacle with means by which the shaft may be caused to rotate, and 5 at its other end with means for engaging the pin in the rotatable member so that, when the shaft is rotated, a simultaneous

rotative movement is imparted to the rotatable member, and that thus the substance ejected through the outlet means in the rotatable member may be of a braid-like form, as, and for the purpose, set forth.

JOHN A. OST.
